ABRADING MACHINE

John B. Hadaway, deceased, late of Swampscott, Mass., by Florence S. Hadaway, executrix, Swampscott, Mass., assignor to United Shoe Machinery Corporation, Borough of Flemington, N. J., a corporation of New Jersey

Application September 22, 1939, Serial No. 296,104.

14 Claims. (Cl. 51—3)

This invention relates to abrading machines and is herein illustrated as embodied in a machine for buffing the bottoms and heel-breast faces of boots and shoes.

In the manufacture of shoes it is customary to buff the bottoms of the soles by means of a machine, which is provided with an abrading tool, for example, an inflated disk-like tool of the so-called Naumkeag type. The spaces between the grains of abrasive material on the operative face of an abrading tool tend to become more or less filled with the dust generated by the operation of the tool upon the work, so that after a time the tool becomes less efficient.

According to one feature of the present invention, there is provided in an abrading machine means responsive to presentation of a piece of work to the abrading tool for directing upon the tool a blast of air to clean it. In the illustrated machine, presentation of a piece of work to the tool lifts the tool slightly and opens a valve in a compressed air conduit leading to a nozzle which is directed toward the operative face of the tool.

If a tool of the inflatable type, such as a Naumkeag tool, is embodied in the machine, it is of course necessary to inflate the tool, and in such case, in accordance with another feature of the invention, a source of supply of compressed air is provided together with means for conducting air at a lesser pressure to the tool to inflate it and means for conducting air at a greater pressure to the nozzle which directs a blast of air upon the tool to clean it.

In a shoe buffering machine it is desirable to make use of a plurality of tools, for example, a Naumkeag tool, to buff the bottom of the sole and a so-called Hildebrand tool to buff the breast and lip of a Louis heel. According to another feature of the present invention, there are provided two tools of different types, a suction hood for removing waste material generated by the operation of the tools, and operator-controlled pneumatic means for moving the tools to locate a selected one of them in operative position in front of the dust hood.

After the shoe has been buffed, it is customary to remove the dust which usually clings to it by directing a blast of air upon it. According to another feature of the invention, compressed air supplied from a common source is employed to inflate and to clean the Naumkeag tool, to move the tools when desired into and out of their operative positions in front of the dust hood and to clean the shoe.

These and other features of the invention, in-

cluding certain details of construction and combinations of parts, will be described as embodied in an illustrated machine and pointed out in the appended claims.

Referring to the accompanying drawings,

Fig. 1 is a side elevation of a machine in which the present invention is embodied;

Fig. 2 is a front elevation of the machine;

Fig. 3 is a view looking down upon the rear part of the machine;

Fig. 4 is a view, partly in section and partly in elevation, showing more particularly the mounting of that one of the Naumkeag tools which may be swung into operative and inoperative positions;

Fig. 5 is a section on the line V—V of Fig. 4;

Fig. 6 is a detail in elevation showing more particularly the nozzles for directing blasts of air upon one of the Naumkeag tools to clean it. The nozzles are shown in the position into which they have been pulled down against the force of a torsion spring;

Fig. 7 is a side elevation showing more particularly the mountings of the Hildebrand tool and the scouring disc;

Fig. 8 is a detail in plan showing more particularly the mechanism for locking the carrier of the Hildebrand tool and the scouring disc in intermediate position;

Fig. 9 is a detail in cross section on the line IX—IX of Fig. 7;

Fig. 10 is a view, partly in elevation and partly in longitudinal section, showing more particularly the construction of the expandible link;

Fig. 11 is a perspective showing the valves for controlling the application of suction to the hoods of the Naumkeag tools and to the hood of the shoe cleaning brush; and

Fig. 12 is a fragmentary elevation showing the treadle control of the valves of Fig. 11 and of the means for supplying compressed air to the nozzles which direct blasts of air upon the Naumkeag tools.

Figs. 3 to 12 inclusive are on larger scales than are Figs. 1 and 2.

Referring first to Fig. 2, the machine has four buffering tools, two main tools 17 and 19 of the inflated Naumkeag disk type for buffering the greater part of the bottom of the sole of a shoe, and two auxiliary tools, a Hildebrand tool 21 (see Patent No. 2,018,671, October 29, 1935) for buffering the breasts of Louis heels as well as for buffering the underside of the curved lips of Continental heels, and a small rotary disk 23 for buffering the portion of the sole which is adjacent to the breast

of a Cuban or similar heel. The Naumkeag tool 19 occupies always a fixed position in front of its dust hood 25. The other Naumkeag tool 17 may occupy a similar operative position in front of its dust hood 27, or it may occupy the inoperative position shown in which it has been swung to one side as far as it can be. The Hildebrand tool and the scouring disk are mounted in a carrier in the form of a hollow member or shell 29 and may occupy three positions, two of which are operative positions and one of which is inoperative. It is shown in the figure in the lower one of its two operative positions, but may be moved up to its intermediate operative position, or still farther up to its inoperative position. The movements of the carrier for the Hildebrand tool and for the scouring disk and of the left-hand Naumkeag tool to position the various tools in the manner described above take place simultaneously and are caused by a compressed air device operated by a treadle.

When a shoe is to be operated upon, the parts of the machine may be at first in the positions shown in Fig. 1, in which the Hildebrand tool and the scouring disk are in position to have the dust caused by their operation carried away by the dust hood 25. The shoe is presented to the selected one of these two tools, depending upon the style of its heel, after which a treadle is manipulated to cause the carrier for these two tools to move to its uppermost position, where the tools are out of the way and at the same time to cause the Naumkeag tool 17 to swing into position in front of its dust hood 27. The sole of the shoe is then buffed by presenting it to the Naumkeag tools, one of which has coarse and the other fine grit. The above is the ordinary procedure. It is, however, possible, if desired, to cause the carrier 29 for the Hildebrand tool and the scouring disk to be moved into an intermediate position in which the scouring disk may be used, and at the same time to swing the Naumkeag tool 17 into position in front of its dust hood. With this location of the tools it is possible to buff the sole of a shoe having a Cuban heel, since the scouring disk and the two Naumkeag tools are all three in operative positions.

The carrier 29 for the Hildebrand tool 21 and the scouring disk 23 (Fig. 7) has the general shape of a hollow cylinder provided with a short right-angled extension and is rotatably mounted between vertically spaced, generally horizontal extensions projecting from and rigid with a bracket 31 which is bolted to the outer end of a vertically swinging arm 33. This arm has the general shape in cross section of an inverted U and its inner end (Fig. 1) is pivoted about the axis of a countershaft 35. Referring again to Fig. 7, the arm is steadied in its vertical swinging movement by an upright guide 37 having a curved edge. The outer end of the arm 33 has a flat side in contact with that side of the guide which is visible in Fig. 7. The upper flat end of the bracket 31 is of substantially the same thickness as that of the guide; and bolts 39, which fasten the bracket 31 to the arm 33, also fasten in place against the opposite side of the guide 37 a plate 41 (see also Fig. 8), the upper portion of which overhangs the upper edge of the bracket 31 and carries a spring-pressed plunger 43 which, as will be explained later, by entering a hole 45 in the edge of the guide 37 serves to lock the arm 33 in its intermediate position. The arm 33 is raised and lowered by means of a yoke 47 (Fig. 1), the upper ends of the arms of which are pivoted to

the arm 33 at 49 and the round stem of which extends down into a small cylinder 51 and carries at its lower end a piston, not shown, which fits in the cylinder. The piston is moved up and down to swing the arm 33 up and down by means of compressed air. To this end, a pipe 53 leads from the top of the cylinder 51 above the piston to the upper end of a pipe 55, the lower end of which is connected to a valve casing, not shown, located in a box 57; a second pipe 59 leads from the bottom of the cylinder 51 below the piston to the upper end of a pipe 61, the lower end of which leads into the same valve casing; and a supply pipe 63 leads from a source of supply of compressed air into the same casing. A plurality of valves, not shown, in the valve casing may be moved into two operative positions. In one position, the supply pipe 63 is connected to the pipe 55 which leads into the top of the cylinder, and the pipe 61 is opened to the atmosphere. In the other operative position, the supply pipe 63 is connected to the pipe 61, and the pipe 55 is opened to the atmosphere. The valves are moved into one operative position by depressing a pedal 65 and into the other operative position by depressing a similar pedal 67, the pedals being so constructed that, depressing one automatically raises the other. When both pedals are in their intermediate position, the supply pipe 63 is closed. The details of construction of the valve mechanism for controlling the flow of air to the cylinder 51 to raise and lower the arm 33 form no part of the present invention, and any suitable valve mechanism may be used.

The compressed air is supplied to the machine for the above and other purposes, presently to be explained, through a main air supply pipe 69 (Fig. 2). This pipe extends down, then toward the observer into a T 71, then upward from the T into the bottom of an air cleaner 73, a pet cock 75 carried by the T providing means for drawing off water or other impurities separated from the air by the cleaner. From the top of the cleaner 73, a conduit 77 comprising nipples and elbows leads into the top of a T 79. From the back of this T a pipe, not shown, leads rearward and then turns to the right across the rear part of the machine, said pipe terminating in an elbow 81 (Fig. 1) which leads into one end of a union 83. To the other end of this union is connected one end of a pipe 85, the other end of which is connected to the horizontal opening in a T, (not shown because it is in front of and would obscure the showing of the cylinder 51), the upper and lower openings of which are connected respectively with a pipe 87 and with the pipe 63. The pipe 87 leads through certain pressure gages to other parts of the machine. Disregarding for the moment this pipe 87, it will be seen that compressed air, at whatever pressure it is supplied, flows from the main supply pipe 69, through the air cleaner and the various conduits described above, directly to the box 57 in which is located the valve mechanism for controlling the flow of air to the cylinder 51 and thus swinging up and down, when desired, the arm 33 by which the Hildebrand tool and the scouring disk are carried.

The two last-named tools are rotated, except when they have been moved up to their highest inoperative position, by a round belt 89 (Fig. 7) which passes around a pulley 91 fastened to the top of a slightly inclined shaft 93. This belt extends through the hollow in the arm 33 to the rear of the machine, one run passing over a guide pulley 94 (Fig. 3), and around a grooved pulley

95, which is loose on the countershaft 35 but is normally held to rotate therewith by a friction clutch member 97. This friction clutch member 97 is fast to the left-hand end of a small shaft 99, which is concentric with the countershaft 35 and is rotatably and slidably mounted in a bearing 101, said small shaft 99 carrying near its right-hand end a disk 103. Extending respectively over and under the disk are the arms of a fork formed at the outer end of a bell-crank lever 105 pivoted about a vertical pivot 107, each arm carrying two pins, one on each side of the disc 103, the two pins in the upper arm being indicated at 109. A tension spring 111 tends at all times to swing the bell-crank lever 105 clockwise and thus to hold the friction clutch member 97 in contact with one side of the pulley 95, so as to drive the pulley and hence to rotate the Hildebrand tool and the scouring disk. One arm of the bell-crank lever 105 carries a small roll 113; and when the arm 33, which carries the two tools just mentioned, is swung to its uppermost position, the projecting right-hand end of the pivot pin 49 strikes the roll, rocks the bell-crank lever counterclockwise and moves the friction clutch member 97 away from the pulley 95, so that the Hildebrand tool and the scouring disk are no longer rotated.

When the carrier 29 for the Hildebrand tool and the scouring disk is moved up by the upward swing of the arm 33, it is at the same time given a partial rotation to the left, as viewed in Fig. 1. Referring now to Figs. 7 and 9, the mounting of the carrier 29 in the bracket 31, which is bolted to the outer end of the swinging arm 33, and the mounting of the Hildebrand tool and the scouring disk in the carrier will be described. The carrier 29 has a generally cylindrical main portion and a short cylindrical extension at right angles to the main portion. It is swung about the axis of the inclined shaft 93 by means of a bent rod 115, which is pulled to the left, as will presently be explained, when the arm 33 is swung up. The rod 115 is pivoted at 117 between ears formed on a small bracket 119, which is fastened to a rotatable collar 121. This collar rests upon the upper one of the two horizontal extensions of the bracket 31 and has on its underside a hub which extends down through a bore or bearing in said extension. The hub of the collar 121 is held from vertical movement by a screw 122, which is threaded through a wall of the extension of the bracket 31 and extends into an annular groove in the periphery of the hub. The shaft 93 is made in two parts, an upper part having at its lower end a collar 123 and a downwardly projecting key 125 and a lower part having at its upper end a keyway to receive the key. A headed bushing 127 carried by the collar 121 extends through said collar and receives the upper part of the shaft 93, the pulley 91 resting upon the head of the bushing 127 and upon the top of the collar 121. That part of the hub 121, which projects down below the upper generally horizontal extension of the bracket 31, fits into the upper end of the main part of the carrier 29. Inside the carrier 29 is a sleeve 131, which is fastened to the carrier by screws, one of which is shown at 133 and which is connected to the hub of the collar 121 by dowel pins 135. Below the sleeve 131, a spiral gear 137 is pinned to the shaft 93, said gear resting upon a block 139 which is fastened to the carrier 29 by a screw 141 and has a central bore to serve as a bearing for the lower

part of the shaft 93. The lower end of the carrier 29 rests upon the upper face of the lower extension of the bracket 31 and is rotatable about the upper end of a cylindrical bearing member 143 which projects up through a bore in said lower extension of the bracket 31 and is held in place by a set screw 145. With the construction described above, the carrier 29 will be rocked about the axis of the shaft 93 in one direction or the other, when the rod 115 is pulled to the right or to the left.

The gear 137 meshes with and drives a gear 147 on the shaft upon which the Hildebrand tool 21 is mounted. The gear 147 in turn meshes with and drives a gear 149 on a shaft 151, which carries at its outer end a small spiral gear 153, said gear meshing with another small spiral gear 155 on a small inclined shaft 157, to the lower end of which the scouring disk 23 is fastened. The shaft 151 is in two parts connected by a key and keyway; and the housing 158, in which the outer part of the shaft 151 and the disk shaft 157 are mounted, is detachably fastened to the extension of the carrier 29. Referring to Fig. 2, where the housing 158 appears in end elevation, it will be seen that the shape of the housing and the inclination of the shaft of the scouring disk 23 are such that that portion of the bottom of the sole of a shoe which is adjacent to the base of the Cuban heel may be buffed.

As has been explained, when the arm 33, upon the outer end of which is rotatably mounted the carrier 29, is swung up, the carrier is rotated by pulling to the left (Fig. 7) the rod 115. This rod is connected by a turnbuckle 152 to one end of another rod 154, the other end of which is pivoted at 156 to the lower end of a bell-crank lever 159 pivoted to the arm 33 at 161, the upper end of the bell-crank lever being pivoted at 163 to the upper end of a bent link 165, the lower end of which is pivoted at 167 to a small bracket carried by the frame of the machine. Thus, when the arm 33 is in its lowest position, the carrier 29 occupies a position shown in Figs. 2 and 7 with the Hildebrand tool in front of the dust hood 27; and when the arm is raised the carrier 29 is rotated to move the Hildebrand tool and the scouring disk farther away from the observer, as viewed in Fig. 2; and as the arm approaches its highest position, the pin 49 (Fig. 3) contacts with the roll 13 on the bell-crank lever 105 and disconnects the Hildebrand tool and the scouring disk from their driving mechanism. When the arm 33 and the carrier 29 are in their lowermost positions, the left-hand Naumkeag tool 17 (Fig. 2) has been swung to the left to its outer inoperative position; and when the arm has been swung to its uppermost position the left-hand Naumkeag tool occupies the same position with respect to the dust hood 27 that the other Naumkeag tool 19 occupies with respect to its dust hood 25.

The Naumkeag tool 17 (Fig. 2) is detachably mounted in the usual manner at the lower end of a hollow upright spindle 169, this spindle in the illustrated machine being rotatable in bearings in a bracket 171, which is mounted for horizontal swinging movement about an upright stationary rod 173. This horizontal swinging bracket is connected to the vertically swinging arm 33 by an extensible link, indicated as a whole at 175 in Fig. 2 and shown in detail in Fig. 10. The link is connected at one end to the arm 33 by a ball-and-socket joint and at the other end to the bracket 171 by a joint of the

same kind. As shown, this link is in its full extended condition, in which it will cause the left-hand Naumkeag tool 17 (Fig. 2) to be moved in front of the dust hood 27 when the arm 33 is swung to its uppermost position. At times, however, the arm is swung to an intermediate position in which the Hildebrand tool and the scouring disk 23 are still being rotated and the scouring disk may be used; and it is desirable, when the two tools just mentioned are in this intermediate position, that the left-hand Naumkeag tool should be in operative position in front of its dust hood 27, so that this Naumkeag tool, as well as the other Naumkeag tool 19, may be used. It is for this reason that an extensible link is provided. When it is desired to move the arm 33 up from its lowest to its intermediate position, the extensible link 175 is shortened; and at the same time the locking plunger 43 (Fig. 8) is freed so that it may enter the hole 45 in the curved face of the upright guide member 37. This locking plunger is normally held in inoperative position by a pawl 177 pivoted at 179 to the arm 33 and held by a torsion spring 181 in such position that the operative end of the pawl engages a collar 183 on the plunger, which is being urged at all times by a compression spring 185 to move to the left and to enter the hole 45 when it is in register with the hole. When the extensible link is shortened, a push pin 187 is moved to the right (Fig. 10) to swing the pawl and thereby free the locking plunger 43. In Fig. 10 the extensible link 175 is shown in its extended condition, the link comprising two sections 189, 191 connected by a turnbuckle 193, the section 189 extending into a socket in a cap 195, in which it is slideable. The cap has a stem provided at its outer end with a ball forming a part of the ball-and-socket joint which connects the link with the swinging arm 33. Extending through and fastened to a lug on the arm 33 is a cylindrical member 197, the left-hand end of which forms part of the ball-and-socket joint, the push pin 187 being loosely mounted for sliding movement in a central bore in this member. When the link 175 is extended, as shown, this pin is inoperative, but when the link is shortened the pin is pushed to the right to swing the tail of the pawl 177 and thereby (Fig. 8) free the locking plunger 43. The link is held in extended condition by means of balls 199 which are located partly in holes extending through the wall of the cap 195 and partly in a circumferential groove in the section 189 of the link, said balls being thus held by a locking sleeve 201 slideably mounted on the cap 195 and constantly urged to move to the left by a compression spring 203, the extent of left-hand movement of the sleeve being limited by a screw 205 threaded through the wall of the sleeve and extending into a groove 207 formed in the wall of the cap. When, now, it is desired to shorten the link 175, the locking sleeve is pulled to the right to release the balls, and the section 189 of the link is pushed into the cap 195 until a second circumferential groove 209 in the section 189 is in register with the balls 199, whereupon the locking sleeve is released and locks the link 175 in its shortened condition. When the section 189 is pushed into the cap 195 its right-hand end pushes to the right a small pin 211, which is slideable in a bore in the stem of the cap, said spring acting through a ball 213 to move the push pin 187 to the right and thus to swing the pawl 177 so as to free the locking plunger 43 (Fig. 8).

The compressed air, which enters through the supply pipe 69 (Fig. 2) and passes through the air cleaner 73, serves not only to raise and lower the Hildebrand tool and the scouring disk and simultaneously to swing the Naumkeag tool 17 into and out of operative position, as has been described, but serves also to inflate the Naumkeag tools, to remove dust from said tools, and to provide two air blasts to remove dust from the shoe after the shoe has been buffed and while it is being presented to a cleaning brush, later to be described. As has been explained, air under full factory pressure is used to raise and lower the Hildebrand tool and the scouring disk. Air under full factory pressure is also used to remove dust from the shoe, but air, which may be at a somewhat reduced pressure, is used to clean the scouring disk and the Naumkeag tools, and air, which is at a greatly reduced pressure, is used to inflate the Naumkeag tools.

The pipe 81, which as has been explained is connected at its lower end to the pipe 63, and therefore contains air at full factory pressure, leads up into a large reducing valve 215 having attached to it a pressure gage 217. From the bottom of this large reducing valve leads a T to which are connected two pipes 219, 221. The pipe 219 leads to a second smaller reducing valve 223, having a second pressure gage 225; and from this reducing valve 223 runs a pipe 227, which is connected to a T at 229. A horizontal pipe 231 leads from this T through a rubber tube 233 into a chamber which communicates with the top of the hollow shaft 169, upon the lower end of which the Naumkeag tool 17 is mounted; and a second horizontal pipe 235 leads from the T 229 through piping, not shown, into a similar chamber which communicates with the top of the hollow shaft, upon the lower end of which the other Naumkeag tool 19 is mounted. The pressure used to inflate the Naumkeag tools is from 1 to 5 pounds per square inch. The pressure used elsewhere is from 75 to 100 pounds per square inch, depending upon the pressure of the compressed air system in the factory in which the machine is being used, the large pressure reducing valve 215 being provided to ensure that the pressure in certain pipes does not rise above 100 pounds per square inch. The vertical pipe 221, which leads from the large reducing valve 215, ends in a T 237. From the left-hand branch of this T a horizontal pipe 239 leads through a rubber tube 241 to a mechanism, presently to be described, for directing blasts of air upon the Naumkeag tool 17 to clean it; and from the right-hand branch of the same T 237 a horizontal pipe 243 leads to a mechanism for directing blasts of air upon the other Naumkeag tool 19.

Inasmuch as the two Naumkeag tools are similarly constructed and mounted, except that the tool 17 is mounted on the swinging bracket 171 and consequently the rubber tubes 233, 241 are provided, only the construction and mounting of the Naumkeag tool 17 will be described in detail. Referring to Fig. 4, the tool 17 has the usual small tapered hollow stem, which fits in a tapered socket in the lower end of the bottom of the hollow vertical shaft 169. Inasmuch as this shaft is mounted for vertical sliding movement so that, when the sole of a shoe is pressed up against the tool the shaft will be pushed up and thereby open a valve to cause a blast of air to be directed upon the tool, it is desirable that the pulley which rotates this tool shaft should

exert no sidewise pull upon the shaft. To this end a long bearing sleeve 247, which is clamped by a pinch screw 249 in a split lug on the bracket 171, has a head at its upper end between which and a nut 251, threaded on the sleeve 247, is 5 clamped the inner ring 253 of a ball bearing, the outer ring being carried by a pulley 257. Thus the pulley rotates about the inner ring and exerts its sidewise thrust upon the stationary sleeve 247. The pulley is connected with the shaft 169 in 10 the following manner. On the upper face of the pulley is a thin boss to which is fastened, by screws 261, a driving member 259 (Fig. 5) in the form of a disk having in its upper side four grooves spaced apart 90°. Into two of these 15 grooves, which are in register, extend, respectively, two short arms 263, said arms projecting from opposite sides of a hub 265, which is fastened to the shaft 169. A cover 267 is also fastened to the grooved disk 259 and to the pulley 20 257 by the screws 261. On the upper portion of the shaft 169 is fastened a collar 269 having a flat upper face, above which is a roll 271 carried by a bent lever 273 which is pivoted at 275 to the bracket 171 and the normal position of which 25 may be regulated by means of a screw 277, which is threaded through the lever and abuts the bracket 171 so as to hold the roll 271 just out of contact with the top of the collar 269. When the shaft 169 is pushed up by the operator, as he 30 holds the bottom of a shoe up against the Naumkeag tool 17, the bent lever 273 is rocked counterclockwise, and its upper end rocks clockwise a small lever 279 pivoted at 281, whereupon the upper end of this small lever pushes to the right a sliding pin 283 to open a spring pressed ball valve 285 in a fitting at the end of the tube 241, and thereby admits compressed air into 35 the chamber 287. From this chamber a pipe 289 leads to a connector 291 (Fig. 6), in which is 40 rotatably mounted one end of a generally horizontal fitting comprising a pipe 292 closed at its outer end and having leading therefrom two curved nozzles 293 which, when in operative position as shown in Fig. 4, direct two converging blasts of air upon the rear portion of the Naumkeag tool to clean the tool and to blow the dust into the dust hood. The closed pipe 292 is mounted in a bracket 295, being rotatably held in a socket in the bracket by an inclined plate 297, which is fastened to the bracket 45 by a screw 299. The hub of a handle 301 is fastened to one end of the pipe 292 to provide means for turning the pipe to withdraw the nozzles from beneath the tool when it is desired to remove and replace the tool. A torsion spring 303, fast at one end to the bracket 295 and at the other end to the hub of the handle, tends at all times to swing the nozzles into the operative position shown in Fig. 4, a stop screw 305, threaded through the handle and adapted to contact with the bracket, providing means for adjusting the operative positions of the nozzles. When it is desired to remove the Naumkeag tool, the nozzles 50 may be swung down into the position shown in Fig. 6. A light spring 274 (Fig. 4), which rests upon the cap 267 and at its upper end engages a flange formed on the collar 269, serves to counterbalance part of the weight of the shaft 169 of the Naumkeag tool. The shaft, when no shoe is being operated upon, occupied its lowered position but may be pushed up as far as a collar 276, which is fastened to the shaft, will 55 permit.

After the buffing operations upon the shoe have 75

been completed, such dust as may cling to the shoe is removed by presenting the shoe to a large rotating brush 307 (Fig. 2) located in a dust hood 309; and while the shoe is being presented to the brush two blasts of air are directed upon the shoe, one from above and one from below, in directions which are respectively diagonally downwardly and diagonally upward. These two blasts are emitted from small perforations formed, respectively, in an upper horizontal pipe 311 and in a lower horizontal pipe 313, both pipes having their right-hand ends closed by caps. Air is supplied to these perforated pipes from a pipe 315 (see also Fig. 12) which leads from the T 19 down into a valve casing 317 containing a valve, not shown, which is normally held closed by a spring, not shown, and has a stem 319 which, when the valve is closed, projects considerably from the casing so that by pushing the stem of the valve to the left the valve may be opened. Leading from the bottom of the valve casing is a conduit consisting of various fittings, which terminates in an elbow 321, from which leads the lower end of an upright pipe 323, said pipe being connected by T's, and various fittings, to the open ends of the perforated blast pipes 311, 313.

The dust hoods 25, 27 for the Naumkeag tools and the dust hood 309 for the cleaning brush are part of a common structure which is connected at its rear end (the right-hand end as viewed in Fig. 1) to the blower system of the factory in which the machine is installed, so as to apply suction to the hoods. In order to apply 35 all the force of the suction to the Naumkeag hoods when the Naumkeag tools are being used and to apply all of it to the cleaning brush when that brush is being used, separate conduits are provided which lead from the dust hoods of the Naumkeag tools and from the hood of the cleaning brush. These three conduits are shown in Fig. 11 near the rear of the machine where they are side by side, the outer conduits 325, 327 leading from the Naumkeag dust hoods and the middle conduit 329 leading from the dust hood of the cleaning brush. Three valves 331, 333, 335, fast to a common horizontal rotary shaft 337, are provided for closing the conduit 329 and simultaneously opening the conduits 325, 327 40 when the Naumkeag tools are being used, and for closing the conduits 325, 327 and opening the conduit 329 when the cleaning brush is being used. In order to rotate the shaft 337 through 90° back and forth, from the position shown in 45 the figure, to a position in which the conduits leading from the Naumkeag dust hoods are closed, the shaft has fastened to it a crank arm 339, to which is pivoted one end of a two-part link 341, the parts of which are connected by a turnbuckle. One end of this link is pivoted at 50 343 to an arm 345, the hub of which is fast to a rock shaft 347. Also fastened to this rock shaft by a pinch screw 349 is the split hub of a second arm 351, the outer end of which is pivoted at 55 353 to the upper end of a two-part treadle rod 355. The lower end of this treadle rod is pivoted at 357 to a treadle 359, said treadle being pivoted at 361 to the frame of the machine and being normally held up as far as a stop screw 363 will 60 permit by a tension spring 365. In the positions of parts shown in Figs. 11 and 12, suction is being applied only to the conduits 325, 327 which lead from the Naumkeag dust hoods, and no blasts of air are being delivered from the perforated pipes 311, 313 (Fig. 2) into the hood of 65 70 75

the cleaning brush 307. When, however, the treadle 369 is depressed to rock the arms 345, 351 clockwise, suction will be applied only to the conduit 333, and at the same time the screw 349 will rotate a small bell crank lever 367, which is pivoted at 369, to cause the lower arm of this bell-crank lever to push to the left the stem 319 of the valve in the casing 317 and thereby to open the valve so that blasts of air are delivered from the perforated pipes 311, 313 upon a shoe which is being presented to the cleaning brush 307.

The machine is driven (Fig. 1) from an electric motor 371 through a belt 373, which passes around a small pulley on the shaft of the motor and around a larger pulley 375 on a horizontal shaft 377, which is rotatably mounted in bearings in the frame of the machine. A larger pulley 379, mounted upon the same shaft 377, has passing around it a long narrow belt 381 from which, directly or indirectly, all the tools of the machine are rotated. This belt has two substantially vertical runs, one of which appears in Fig. 1, the directions of movement of the various runs of the belt being indicated in Figs. 1 and 3 by the arrows. Starting with the substantially vertical run directly behind the run which appears in Fig. 1, the belt 381 leads up over a pulley 383 (Fig. 3), then forward around a pulley 385 (Fig. 4) which is rotatable about a vertical spindle carried by a small bracket 387, said bracket being fastened to the upright rod 173 about which the bracket 171 swings. The pulley 385 has two grooves, one to receive the belt 381 and the other to receive a short belt 389 which passes around the pulley 385 and around the pulley 257 so as to drive the Naumkeag tool 17. Returning to the main belt 381, this belt runs from the pulley 385 to the rear around a pulley 391 (Fig. 3), then forward around a pulley 393 (Fig. 1) which drives the Naumkeag tool 19, then to the rear over a pulley 395 on the countershaft 35 and finally down and around the pulley 379. The cleaning brush 307 is driven by its short belt 397, which passes around a pulley 399 on the brush shaft and around a pulley 401 on the countershaft 35. In order to hasten the coming to rest of the moving parts after the power has been shut off from the motor, a brake shoe 403 (Fig. 1) may be applied to the under face of the pulley 379 by means of a treadle 405, which is pivoted at 407 to the frame of the machine and carries the braking shoe at its outer end.

Although the invention has been set forth as embodied in a particular machine, it should be understood that the invention is not limited in the scope of its application to the particular machine which has been shown and described.

Having described the invention, what is claimed as new and desired to be secured by Letters Patent of the United States is:

1. An abrading machine having in combination, an abrading tool, a support for said tool, said tool being constructed and arranged to be displaced relatively to said support by pressure of the work, means for operating the tool, and means responsive to displacement of the tool for directing upon the tool a blast of air when a work-piece is pressed against the tool.

2. An abrading machine having in combination a rotary abrading tool of the disk type, a shaft upon which said tool is mounted, a support in which said shaft is displaceable axially when the tool is pressed against by the work, means for driving said shaft, and means responsive to axial

displacement of said shaft for directing upon the tool a blast of air when a work-piece is pressed against the tool.

3. An abrading machine having in combination, an abrading tool, a support for said tool, said tool being constructed and arranged to be displaced relatively to said support by pressure of the work, means for operating the tool, a nozzle for directing a blast of air upon the tool, a conduit through which air under pressure is supplied to the nozzle, a valve in the conduit, and means responsive to displacement of the tool by pressure of a work-piece for opening the valve.

4. An abrading machine having in combination, a rotary abrading tool of the disk type, a support for said tool, said tool being constructed and arranged to be displaced relatively to said support by pressure of the work, a hood for carrying away dust generated by the operation of the tool on a piece of work, a source of supply of compressed air, two nozzles arranged to direct two blasts of air at an angle to each other upon the face of the tool and toward the hood, and means responsive to displacement of the tool by the pressure of a work-piece for controlling the flow of air through the nozzles.

5. An abrading machine having in combination, an inflated abrading pad, a rotary substantially upright spindle to the lower end of which the pad is fastened, a hood for carrying away dust generated by the operation of the tool, a source of supply of compressed air, and two nozzles for directing two blasts of air at a converging angle to each other and toward the hood upon the operative face of the tool.

6. An abrading machine having in combination, a main tool, means for rotating said tool about a substantially vertical axis, an auxiliary tool, means for rotating said tool about a substantially horizontal axis, a suction hood for removing waste material generated by the operations of the tools, and operator-controlled means for moving the main tool horizontally and the auxiliary tool vertically to locate first one tool and then the other in front of the dust hood and for simultaneously moving either tool to an out-of-the-way position when the other tool is moved to an operating position in front of the dust hood.

7. An abrading machine having in combination, a main tool, an auxiliary tool, a suction hood for removing waste material generated by the operation of the tools, said tools being both capable of being moved into and held in two positions, one of which is near to and the other of which is remote from the hood, the auxiliary tool being also capable of being moved into and held in an intermediate position, and operator-controlled means for simultaneously moving the main and auxiliary tools to cause the main tool to occupy its position near to the hood and to cause the auxiliary tool to occupy either its remote or its intermediate position as may be desired.

8. An abrading machine having in combination, a main tool, an auxiliary tool, a suction hood, said tools being mounted for bodily movement in unison such that when one is moved in front of the hood the other is moved away from the hood, a source of supply of compressed air at two different pressures, a cylinder, a piston in the cylinder movement of which moves the tools, means for supplying air at a comparatively low pressure to one of the tools to inflate it, and operator-controlled means for supplying air

at a higher pressure to the cylinder to cause movement of the tools.

9. An abrading machine having in combination, a main tool, an auxiliary tool, a suction hood for removing waste material generated by the operation of the tools, an arm by which the main tool is carried, said arm being pivoted for swinging movement about a substantially vertical axis to move the main tool into and out of operative position with respect to the hood, a second arm by which the auxiliary tool is carried, said arm being pivoted for swinging movement about a substantially horizontal axis to move the auxiliary tool into and out of operative position, and operator-controlled means including a connection between said tools for simultaneously swinging either tool into operative position and the other tool into inoperative position.

10. An abrading machine having in combination, a main tool, an auxiliary tool, a suction hood for removing waste material generated by the operation of the tools, carriers for the tools, operator-controlled means for moving the tool carriers to locate the main tool in front of the hood and to locate the auxiliary tool in an inoperative position remote from the hood, and means for varying the distance between the carriers in such manner that moving the main tool into position in front of the hood moves the auxiliary tool into a position intermediate between its position in front of the hood and its remote inoperative position.

11. An abrading machine having in combination, a suction hood, an inflatable tool movable into and out of operative relation to the hood, means including a cylinder and a piston in the cylinder for moving the tool, a nozzle for directing a blast of air upon the tool to clean it, a source of compressed air under pressure, and

means for conducting compressed air into the tool, into the nozzle and into the cylinder.

12. An abrading machine having in combination, a suction hood, an inflatable tool movable into and out of operative relation to the hood, means including a cylinder and a piston in the cylinder for moving the tool, a nozzle for directing a blast of air upon the tool to clean it, a pipe adapted to direct a blast of air upon the shoe to clean it, a source of compressed air under pressure, and means for conducting compressed air into the tool, into the nozzle, into the cylinder and into the pipe.

13. An abrading machine having in combination, a suction hood, an inflatable tool movable into and out of operative relation to the hood by means including a cylinder and a piston in the cylinder, a nozzle for directing a blast of air upon the tool to clean it, a source of supply of compressed air under two pressures, means for conducting air at one pressure into the tool to inflate it, and means for conducting air at a greater pressure into the nozzle and into the cylinder.

14. An abrading machine having in combination, a tool for abrading the work, a brush for cleaning from the work the dust which clings to it, a suction hood for removing the dust cleaned from the work, a pipe arranged to direct upon the work while it is being presented to the brush a blast of air, means for applying suction to the hood, means for supplying compressed air to the pipe, and a common operating means for said suction applying means and said compressed air supplying means constructed and arranged to enable the operator to control the application of suction and the supply of compressed air simultaneously.

FLORENCE S. HADAWAY,
40 Executrix of the Will of John B. Hadaway, De-
ceased.
